US0D1014273S

(12) **United States Design Patent** (10) Patent No.: **US D1,014,273 S**
(45) Date of Patent: ** *Feb. 13, 2024

(54) **BOTTLE**

(71) Applicant: **Roche Diagnostics Operations, Inc.**,
Indianapolis, IN (US)

(72) Inventor: **Alex Weymann**, Mannheim (DE)

(73) Assignee: **Roche Diagnostics Operations, Inc.**,
Indianapolis, IN (US)

(*) Notice: This patent is subject to a terminal disclaimer.

(**) Term: **15 Years**

(21) Appl. No.: **29/816,594**

(22) Filed: **Nov. 23, 2021**

(30) **Foreign Application Priority Data**

May 25, 2021 (EM) 008551618-0001

(57) **CLAIM**

The ornamental design for a bottle, as shown and described.

DESCRIPTION

The sole FIGURE is a perspective view of a bottle showing my new design.

The evenly broken lines are shown for the purpose of illustrating parts of the article that form no part of the claim. The dot-dash lines represent the boundaries of the claim and form no part thereof.

1 Claim, 1 Drawing Sheet
